UNITED STATES PATENT OFFICE.

FREDERICK H. SEARLE, OF TOLEDO, OHIO, ASSIGNOR TO HIMSELF, ROBINSON P. SEARLE, OF TOLEDO, OHIO, AND HENRY A. SEARLE, OF COUNCIL BLUFFS, IOWA.

GREASE-CONTAINER.

1,265,533.

Specification of Letters Patent.

Patented May 7, 1918.

Application filed July 19, 1917. Serial No. 181,456.

To all whom it may concern:

Be it known that I, FREDERICK H. SEARLE, a citizen of the United States, residing at Toledo, in the county of Lucas and State 5 of Ohio, have invented a certain new and useful Improvement in Grease-Containers, of which the following is a specification.

The invention relates to packages adapted 10 to contain and dispense lubricating grease or other viscid material, and the object of the invention is to provide a simple, economically manufactured container from which the grease may be easily expelled in the desired quantities, from either end, 15 closed efficiently for transportation or storage, and which may be easily and quickly refilled for another discharge.

The invention consists in certain novel 20 features and details of construction and arrangement by which the above objects are attained, to be hereinafter described and claimed.

The accompanying drawings form a part 25 of this specification and show the invention as it has been carried out in practice.

Figure 1 is a side elevation of the container in the closed condition.

Fig. 2 is an elevation of one end or head.

Fig. 3 is a similar view of the other end or head.

Fig. 4 is an axial section taken on the line 4-4 in Fig. 3, and corresponding to Fig. 1.

Fig. 5 is a similar section showing the container in the partially discharged condition.

Fig. 6 is a transverse section, on the line 6-6 in Fig. 4.

Fig. 7 is a similar section taken on the line 7-7 in Fig. 5.

Fig. 8 is a face view of the plunger for expelling the contents.

Fig. 9 is an elevation of an extension 45 nozzle.

Similar letters of reference indicate the same parts in all the figures.

A is a cylinder, preferably of fiber, paper or like inexpensive material, having at each 50 end a permanently attached collar A¹ of metal, screw threaded to receive sheet metal heads B B¹ threaded to match interchangeably upon the collar at either end. The head B is simply a closed cover applied on one 55 end of the cylinder A, and the head B¹

which will be termed the delivery head, has a nozzle C on its outer face, shown as extending radially from the center and closed by a screwcap C¹.

Within the cylinder is a plunger or follower D, fitting piston-wise therein, consisting preferably of a circular disk of wood having a packing-ring D¹ of fabric or the like extending around its periphery to serve in making a close joint between the movable follower and interior of the cylinder. The disk is recessed at the center on both faces as indicated at d.

In filling the container the follower D is located at or near one end of the cylinder 70 covered by the closed head B, and the remaining portion of the body or cylinder is then filled with grease M, and the delivery head B¹ applied with its nozzle C closed by the screwcap C¹. In this condition the 75 filled container is ready for transportation or storage.

To discharge the grease the closed head B is removed to expose the face of the follower D, the screwcap C¹ is removed from 80 the nozzle, and by thrusting on a rod F or other suitable implement inserted through the open end of the cylinder with its point engaged in the conical recess d in the exposed face, the plunger is forced toward the 85 opposite end of the cylinder expelling a corresponding quantity of grease through the nozzle C.

When by a single or a series of such thrusts or application of pressure the contents has been discharged as described, the delivery head B¹ is removed and the closed head B substituted therefor, the cylinder is again filled and the delivery head B¹ applied at the opposite end. The container 90 is thus conditioned again to deliver by a reverse movement of the follower D. The filling and emptying operations may be repeated indefinitely.

C² is a tubular extension having a screw-thread at one end C³ matching to the thread of the nozzle C and is applied to the latter in place of the screw cap C¹ to lengthen the nozzle as in Fig. 5, and permit the grease or other contents to be directed to 105 the desired point or to the portion of the machinery to be supplied.

It is intended to join the extension C² detachably to the container or otherwise present it therewith, and also to supply a 110

suitable thrusting tool F, but the extra nozzle or extension may be omitted, and in the absence of the tool F, any stick or rod of the proper length will serve, preferably 5 pointed to engage the central recess d in the follower D to insure equal distribution of strain on the latter in the discharge movement and thus avoid any tendency to cramp or bind in the cylinder.

10 Modifications may be made in the forms and proportions and in the materials employed, and the invention may be applied to other uses to which it is adaptable.

I claim:—

15 1. The container described, consisting of a cylindrical body having its ends screw-threaded, interchangeable heads threaded to match to either of said ends, one of said heads having a delivery nozzle and the other 20 closed, a plunger in said body having a central recess in each face and arranged to be exposed by the removal of said closed head, and to be moved axially toward said delivery head by pressure applied through a 25 rod introduced through such open end of said body and engaged in such recess.

2. The container described, consisting of a cylindrical body having its ends screw-threaded, interchangeable heads threaded to 30 match to either of said ends, one of said heads having a radially disposed delivery nozzle and the other closed, a plunger in said body having a central recess in each

face, and arranged to be exposed by the removal of said closed head, and an unattached rod introduced through such open end of said body, having a point adapted to engage such recess, and adapted to move said plunger axially toward said delivery head. 35

3. The container described, consisting of a cylindrical body, removable heads closing the ends of said body, and an unconnected plunger in the latter adapted to be forced axially in either direction without removal 40 from said body by pressure applied thereto through an open end of said body afforded only by the removal of the corresponding head. 45

4. The container described, consisting of a cylindrical body, interchangeable heads closing the ends of said body, and an unconnected plunger in the latter adapted to be forced axially in either direction without removal 50 from said body by pressure applied thereto through an open end of said body afforded only by the removal of the corresponding head. 55

In testimony that I claim the invention above set forth I affix my signature, in presence of two witnesses.

FREDERICK H. SEARLE.
